UNITED STATES PATENT OFFICE.

ARTHUR HAWTREY, OF BUENOS AIRES, ARGENTINA.

SHEARING OR CLIPPING MACHINE.

1,163,819.

Specification of Letters Patent. Patented Dec. 14, 1915.

Application filed April 10, 1913. Serial No. 760,138.

To all whom it may concern:

Be it known that I, ARTHUR HAWTREY, a citizen of the United States of America, residing at 671 Calle Maipu, Buenos Aires, Argentina, have invented certain new and useful Improvements in Shearing or Clipping Machines, of which the following is a specification.

This invention relates to machines for shearing or clipping the wool or hair of animals and for similar uses of the type in which oscillatory members in conjunction with spherical bearings are employed and in which also oscillatory members comprising two rigid fingers and a central finger and a tension pin having a fixed bearing base in the casing have been proposed or employed.

Heretofore in connection with machines of the type referred to certain objections have obtained, principally as a result of the means for applying the tension being liable to serious wear and depreciation incidental to the great vibration to which the parts are subjected and which their construction is unadapted to resist or of their being of such a form that considerable friction occurs in working with a consequent waste of energy and undue heating of the machine.

The present invention is designed with the principal object of remedying the above mentioned defects and to this end consists in providing a novel combination and arrangement of parts whereby the oscillating arm which operates the cutter is supported and actuated in such a manner that the necessary pressure or tension for maintaining cutting contact between the combs and cutters can be applied and maintained in an improved manner. The oscillatory member or lever which comprises rigid outer fingers and a finger adapted to exert pressure or tension on and actuate the cutter, is therefore adapted to maintain its operative relation to the cutter by means of an adjustable semi-spherical support arranged at or near the inner end or heel thereof and a tension pin whereof one end rests upon or against a rigid or immovable seating or base in the casing of the machine and the other end upon the center or thereabout of the said lever or member.

In order that the said invention may be clearly understood and readily carried into effect, I will proceed to describe the same

more fully with reference to the accompanying drawings in which—

Figure 1 is a plan of a shearing or clipping machine having the present improvements applied thereto. Fig. 2 is a longitudinal section taken along the line A—B in Fig. 1. Fig. 3 is a transverse section taken along the line C—D in Fig. 1. Fig. 4 is also a transverse section similar to Fig. 3 illustrating a modified arrangement for effecting the application and regulation of the aforesaid tension or pressure.

The casing or metal cover 1 serves as a handle and as a container for the operating mechanism. The comb 2 is conveniently secured to a seating at the under side of the front part of the casing; the cutter 3 being held in position on the comb by the oscillatory member or lever arm 4 which is provided with two outer rigid horns or fingers and a central pivoted finger for distributing the pressure evenly over the surface of the cutter. The center of movement of the said member or arm 4 is constituted by a bearing 5 adapted to rest on a semi-spherical seating formed or provided on a movable support 6 which extends transversely of the machine and is retained in position by guide pins or screws 7 and actuated by the central screw 8. This arrangement, as will be readily understood, enables the support 6 to be moved upward or downward as a nut on the screw 8. The tension pin 9 bears at or about the center of the said member or arm 4; the said pin having a spherical lower end for that purpose. The upper end of the pin presents a convex bearing face of a semi-spherical curvature whereof the center is common with that of the spherical part at the lower end of the pin. The bearing for the said upper end of the tension pin is constituted by a steel disk 10 which is arranged in a plane parallel with that of the comb seating so as to insure a perfectly even and constant pressure to the member or lever arm 4 and thereby to the cutter throughout its movements. The said disk which serves as a fixed or rigid base for the convex face of the tension pin is retained in position by means of the bushing 11 which is screwed into the cavity formed in the inner side of the upper part of the casing or cover.

The operating lever 14 whereby the oscillating motion is imparted to the member 4

is mounted upon a flanged bushing 12 which receives the upper end of the central screw 8 and which is itself screwed into the upper side of the casing or cover 1; a screw cap or lock nut 13 securing the said bushing in position, which thereby serves as an axis for the movement of the lever 14. One end of the latter is formed so as to serve as the race for the roller 15 carried by the eccentric pin pertaining to the disk 16 on the shaft 17 common to the type of shearing or clipping machines referred to. The other end of the lever 14 is perforated so as to allow of the passage and free play through the same of the tension pin 9 and is formed with a bifurcated termination adapted to closely engage the member or lever arm 4; the close engagement being however of such a character as not to prevent the said member from adjusting itself to the necessary angles which it may be required to assume in relation to the support 6 and the cutter 3 in order to compensate for wear or possible inclination of same.

25 The central screw 8 constitutes the principal member for effecting the adjustment of the tension or pressure as by rotating the same in the one or the other direction the support 6 is raised or lowered and thereby the member or lever 4 is caused to exert more or less pressure on the cutter 3. The said screw 8 is formed or provided with a collar 18 which resides in a recess pertaining to a transverse plate 19 rigidly secured in position by the guide pins or screws 7.

40 The casing or cover 1 has an opening at the lower side of such dimension as to allow the easy mounting and dismounting of all the internal parts, the said opening being provided with cover plates 20 and 21 secured in position in any convenient manner. Upon withdrawing the guide pins or screws 7 the plates 19, 20 and 21 may be readily detached and the whole of the internal parts easily 45 dismounted.

45 In Fig. 4 the central screw 8 is actuated from the upper side of the casing; the lower extremity being coned and seated in a corresponding conical shaped cavity formed in the transverse plate 19. It will thus be seen that the manner of moving the support 6 may be varied without altering the principal mechanism whereby the tension or pressure is applied to the cutter irrespective of the 50 grade of inclination it may assume during its movement. The oscillating operating lever 14, as previously stated, moves rotatively or oscillates on the bushing 12 as an axis and is actuated by the rotation of the eccentric disk 16 carried by the shaft 17; the lever 14 transmitting the resulting oscillatory movement thereof to the member or lever 4 as by means of the bifurcated extremity which engages on the said member or lever 4 as hereinbefore described. As a result of the

member or arm 4 bearing on the semi-spherical surface on the support 6 and of the center of the said bearing coinciding with that of the bushing 12, whatever the degree of inclination of the said arm the latter and the lever 14 move together about the same center; avoiding any sliding or frictional movement between the points of contact of the parts during operation. If it be desired to increase the pressure between 75 the cutter 3 and comb 2 the central screw 8 should be rotated so as to raise the support 6; this movement of the latter will have the effect of raising the bearing or inner end of the member or lever 4 but as the movement 80 of this member at the forward end thereof is limited in the upward direction by the tension pin 9, it follows that the aforesaid raising or upward force at this part of the said member, is converted into downward 85 pressure, which is thus exerted on the cutter.

The operation of the different parts of the mechanism having been described their movements in relation to each other will now be apparent.

90 What I claim and desire to secure by Letters Patent of the United States is:—

1. In a shearing or clipping machine, the combination of a comb, a cutter, an oscillatory member for imparting movement to said cutter, an adjustable semi-spherical support for the inner end of said oscillatory member, means for adjusting said semi-spherical support, means intermediate of said semi-spherical support and said cutter, 100 constructed and arranged to maintain tension on said oscillatory member, and an actuating lever arranged above said oscillatory member and adapted to turn about the same axis and impart movement thereto. 105

2. In a shearing or clipping machine, the combination of a comb, a cutter, an oscillatory member for imparting movement to said cutter, an adjustable semi-spherical support for said oscillatory member, formed on a transverse bar, guides for said support, a screw-threaded member for supporting and actuating said semi-spherical support, means constructed and arranged to maintain tension on said oscillatory member and an actuating lever arranged above said oscillatory member and adapted to turn about the same axis and impart movement thereto. 115

3. In a shearing or clipping machine, the combination of a comb, a cutter, an oscillatory member for imparting movement to said cutter, an adjustable support for the inner end of said oscillatory member, a screw-threaded supporting and actuating member for said adjustable support, means 120 constructed and arranged to maintain tension on said oscillatory member, an actuating lever for said oscillatory member, and a flanged bushing for supporting said actuating lever, said bushing also constituting a 125

130

bearing for said screw-threaded supporting member.

4. In a shearing or clipping machine, the combination of a comb, a cutter, an oscillatory member for imparting movement to said cutter, an adjustable semi-spherical support for the inner end of said oscillatory member, a screw for supporting and actuating said semi-spherical support, means constructed and arranged to maintain tension on said oscillatory member, a bushing arranged above said oscillatory member and adapted to support one end of said screw, a

flange on said bushing, and an actuating lever mounted upon said bushing, supported by said flange, to turn about an axis substantially coincident with the axis of said oscillatory member, and impart movement thereto.

In testimony whereof I affix my signature in presence of two witnesses.

ARTHUR HAWTREY.
